ADJUSTABLE TRESTLE OR THE LIKE

Walter F. Charley, Central Point, Oreg., assignor
of one-half to Earl E. Nill, Medford, Oreg.

Application June 19, 1946, Serial No. 677,676

4 Claims. (Cl. 304—5)

1

The present invention relates to a structural device in the form of a multiple-purpose supporting frame and novel means carried by said frame for various adjustments and levelling purposes.

More specifically, the invention pertains to a leg-equipped U-shaped frame, the legs thereof being provided with coacting and complementary adjusting and levelling devices whereby to permit the frame, as a unit, to occupy desired perpendicular and angular positions in respect to the ground or other supporting surface.

The structure, primarily considered, is designed to serve as a so-called carpenter's saw-trestle or horse, but is such in construction and form as to constitute an adjustable supporting frame for camp tables, for work benches, rug-making frames, and for many other purposes, some of which will be hereinafter set forth.

Briefly, and in carrying out the preferred embodiment of the overall construction, I contemplate the adoption and use of a U-frame, preferably constructed from available pipe lengths, the horizontal pipe being provided with a capping board, or the like, and the vertical pipes constituting the legs and these being bifurcated and the furcations straddling and being adjustably connected with especially constructed fixtures, said fixtures having ground-contacting feet and arcuate racks coacting with detents on said legs in a manner to attain the desired adjusting and levelling results.

Another and obvious object of the invention is to provide a structure of the type herein mentioned which is possessed of simplicity, durability and efficiency, whereby to accomplish desired ends in a reliable and satisfactory manner.

Other objects, features and advantages of the invention will become more readily apparent from the following description and the accompanying illustrative drawings.

In the drawings, wherein like numerals are employed to designate like parts throughout the same—

Figure 1 is an elevational view of a so-called carpenter's horse or saw trestle constructed in accordance with the principles of the present invention.

Figure 2 is a fragmentary view of one end portion of the structure.

Figure 3 is an enlarged elevational view of one of the adjusting and levelling units.

Figure 4 is a fragmentary sectional and elevational view taken through the lower end portion of one of the legs and showing the construction

2

of details and the manner in which they coact with each other.

Figure 5 is a horizontal section on the plane of the line 5—5 of Figure 4, looking in the direction of the arrows.

Figure 6 is a detail elevational view of one of the detents.

Figure 7 is a bottom plan view of one of the legs exposing the V-shaped end of the detent.

10 Figure 8 is a fragmentary elevational view of one of the upper corners of the U-frame.

Briefly, and referring to Figure 1, it will be seen that the main part, the so-called U-frame, is denoted by the numeral 10 and this is provided with 15 a work-supporting cap board or equivalent element 11. The adjusting and levelling units or devices, of which I provide two, are denoted and differentiated by the numerals 12. These are of duplicate construction and a description of one 20 will suffice for both.

The U-frame 10 may be of some construction other than shown, but is preferably made up of three lengths of pipes, a lengthy horizontal pipe 13, and slightly shorter right-angularly disposed 25 pipes 14. The latter pipes constitute the aforementioned legs and are connected to the ends of the pipe 13 by elbows or elbow fittings 15. It is desirable, in certain instances, to employ bolts, as at 16, to facilitate connecting the leg-pipes 30 to the horizontal connective pipe 13. The pipe 13 is provided, adjacent opposite ends, with oppositely projecting clips 17 apertured at their outer ends to accommodate bolts 18 which serve to detachably secure the topping or cap board 11 35 in place. This board has its ends extending beyond the opposite end portions of the frame 10, as shown in Figure 1. The lower ends of the legs are bifurcated, as at 19, to provide furcations 20 and 21 and said furcations straddle the crown portion of the coacting C-shaped levelling and 40 adjusting unit or device 12. Reference being had to Figure 3, it will be seen that the body portion 23 terminates in heads 24 which function as feet. These feet rest on the ground or other supporting surface, as is obvious. The longitudinally bowed or curved member 25 is provided with teeth 45 26 and constitutes a segmental or arcuate rack. The extreme central or crown portion 27 is provided with an outstanding assembling and retaining hook 28 fitting between the furcations 20 and 21 and coacting with a lug 29 to define an entrance opening 30 for the assembling bolt 31 (see Figure 50 4). There is another bolt 32 and this serves to secure the cylindrical fitting or insert 33 in place. 55 Said fitting has its lower end of V-shaped form,

as indicated at 34, and the latter constitutes a detent or tooth adjustably engaging the teeth 26 on the adjusting rack bar or member 25.

As previously stated, the furcations straddle the C-shaped member 23 and the rack bar and the hook and lug 29 fit between the furcations and coact with the hook 28 and lug 30. Thus, the adjuster unit 22 is swingably and slidably connected with the bifurcated legs. There is sufficient play in the connection (the bolt 31 and the parts 28 and 29) to permit the adjuster unit 22 to be bodily shifted in relation to the legs to obtain the desired adjustment results. After the adjustment has been made, the detent 34 engages the selected teeth 26 in the rack-bar, and the bolt 31 rests on the crown spot 27. By sliding the bolt in relation to the hook 28, it can be lifted from contact with said spot 27 and the detent 34 can also be disengaged to attain the desired clearance and shiftable adjustment.

As before stated, the invention herein under advisement is, generally speaking, a U-frame so constructed and equipped as to permit it be attached to a carpenter's saw trestle. By providing the adjusting units or devices 12 and providing the U-frame 10 and capping board 11, an assemblage is thus provided which is, in effect, a supporting frame susceptible of many different uses. That is to say, it can be used as a support for table boards, work benches, embroidery frames, and for many other uses. The device can be used alone or in combination with other corresponding or like devices when it is necessary to employ same in plural relationship.

It is understood that I am not particularly interested in the various functions and purposes for which the supporting frame ultimately be adopted and used, but merely in the construction of the frame itself, as shown in Figure 1 of the drawing.

In view of the foregoing description taken in conjunction with the accompanying drawings, it is believed that a clear understanding of the construction, operation and advantages of the device will be quite apparent to those skilled in this art. A more detailed description is accordingly deemed unnecessary.

It is to be understood, however, that even though I have herein shown and described a preferred embodiment of my invention that the same is susceptible to certain changes fully comprehended by the spirit of the invention as herein described and the scope of the appended claims.

I claim:

1. As a new article of manufacture and as a component part of a structural device of the class described, a C-shaped member having its ends terminating in supporting feet, an arcuate rack-bar carried thereby, a hook mounted on the crown portion, and a lug also on said crown portion associated with the bill of the hook.

2. In a structural device of the class described,

a substantially U-shaped frame including a pair of duplicate vertical legs and a horizontal connecting portion between the upper ends of said legs, said legs being of duplicate construction and each leg having its lower end portion bifurcated to provide a pair of furcations, a retaining bolt passing through the leg at a point inwardly of the outer end portions of said furcations, an insert plugged into the leg and fitting between the furcations, the outer end portions of said insert being of V-shaped form, constituting a detent and being situated within the confines of the leg at points inwardly of the extreme outer ends of said furcations.

3. The structure specified in claim 2, together with an adjuster device for each leg, the adjuster device being adapted to be mounted between the furcations and including a C-shaped member having its outer ends terminating in supporting feet, including an arcuate toothed rack, the teeth being adapted to accommodate the aforementioned detent, and the intermediate portion of said member having an outstanding hook adapted to be connected with the aforementioned bolt.

4. In a structure of the class described, an inverted U-shaped frame, the ends of said frame constituting supporting legs, at least one of said legs having its lower end bifurcated, a bolt mounted in said leg and situated at a point inwardly of the inner ends of the furcations, an insert in the form of a plug, said insert being plugged into the leg between said furcations, the outer end portion of said insert being formed into a detent, an adjuster device comprising a substantially C-shaped member mounted for use and operation between the furcations, the free ends of the C-shaped member constituting supporting feet, the intermediate portion being provided with an outstanding hook and an associated lug, said hook and lug being mounted on and for coaction with said bolt, and said C-shaped member being provided with a toothed arcuate rack, said detent being adapted for coaction with the teeth of said rack.
